UNITED STATES PATENT OFFICE.

JAMES B. ALLEN, OF SAN FRANCISCO, CALIFORNIA.

DISPLAY-FRAME FOR SHOW-WINDOWS.

SPECIFICATION forming part of Letters Patent No. 727,252, dated May 5, 1903.

Application filed July 14, 1902. Serial No. 115,418. (No model.)

To all whom it may concern.

Be it known that I, JAMES B. ALLEN, a citizen of the United States, and a resident of the city and county of San Francisco and State 5 of California, have invented a new and useful Improvement in Display-Frames for Show-Windows, of which the following is a specification.

This invention relates to a device for supporting a hat or similar article in position for display in a store-window; and the invention has for its object to provide a display-frame that will support a hat without marking or disfiguring either the body or the brim and 15 one that will have, besides, a scope or capacity by adjustment for holding hats of different sizes and styles in a variety of positions well adapted to display the article to advantage.

To such ends and object my invention consists in certain novel construction and combination of head, socket, and brim-holding frames, also in certain features of adjustment in combination with said parts, also in certain details of construction of the head and 25 brim-holding frames, producing an adjustable display-frame, all as hereinafter described, and pointed out in the claims at the end of this specification.

The following description explains at length 30 the manner in which I proceed to construct, produce, and carry out my said invention, the accompanying drawings being referred to by figures and letters.

Figure 1 of the drawings is a perspective view of a display-frame embodying my invention. Fig. 2 is a plan or top view, and Fig. 3 a side view. Fig. 4 is a slight modification showing the manner of constructing the head 35 of wood.

The parts of this display-frame are herein 40 designated and referred to as the head *a*, socket *b*, frames *cc*, and supporting-standard *d*. The last-named part is not included among the novel parts of the structure for the 45 reason that it is the same as the ordinary standard commonly used in store-windows to support a block for holding a hat in an elevated position. By removing the block from such a standard the socket *b* of my display-frame can be fitted on the end of that support, and the storekeeper is thereby enabled 50 to utilize the standards he has already in use.

In that case only the head and the connected parts need be furnished, and for that purpose the socket *b* is slotted longitudinally or is 55 formed in two parts, as shown in Fig. 3, to fit different sizes or thicknesses of standards.

A hinge-joint 2, having a clamp-screw 3 with a thumb-nut 4, unites the socket and the head and allows the latter piece to be 60 tilted from a horizontal position and set at varying angles. The head *a* is best made by bending a rectangular strip of sheet-metal so as to form two parallel sets of tubes or apertures 55 on opposite sides of the central point 65 at which the socket is fixed; but the head can also be made of a solid block of wood, as shown at *a'* in Fig. 4, by boring the holes 66 through it. These apertures or holes constitute sockets to receive the wire legs 77 of the frames *c*, 70 and the wires are fitted in them sufficiently close or tight to hold in position without requiring set-screws or other fastening means.

The frame *c* is produced from a single strip of wire by bending the same in a curve at 75 the middle, so as to bring the two ends parallel and pointing in the same direction, and then bending the straight members twice at right angles, as shown at 9 10, bringing the straight members parallel with the middle 80 portion 8, but a short distance above the plane of the middle portion. Bending the frame in this manner throws the middle portion 8, on which the hat is carried, somewhat below the level of the head *a*, and when the hat *x* is 85 placed on the frame, with the brim *y* resting on the supports 88 at front and back, the head *a* will lie within the crown of the hat and be hid from view, so that nothing but the standard will be exposed. 90

In connection with the present custom of displaying their goods in the show-window it is the practice among storekeepers to insert a price-ticket in the band of the hat, where it can readily be seen. In most cases, however, 95 this is found objectionable on account of the liability to stretch and disfigure the band and also to permanently mark the body of the hat, especially where under exposure to a strong light the portion of the body covered 100 by the ticket soon becomes a different shade or color from the other part not so protected from the light. To overcome these objections, I provide a ticket-holding device in con-

nection with my improved display-frame by means of which the price-ticket is supported directly in front of the hat it is intended to mark without being carried by the hat. This 5 device consists of a rod *e*, having a double bend or offset, as shown in Fig. 3, and a straight member for inserting in a socket 13, provided in the head *a*. The ticket is fixed in the front end, which has a hook 14 for that 10 purpose. By this attachment to the frame the price-ticket is supported in front of the brim instead of on the hat.

Having thus fully described my invention, what I claim as new therein, and desire to secure by Letters Patent, is—

- 15 1. A display-frame comprising a head having apertures as described, wire frames having parallel legs adapted to fit the apertures in the head and brim-supporting portions, and
- 20 a socket under the head adapted to fit a supporting-standard.

2. In a display-frame, the combination of a suitable standard, a head having a socket to receive the standard, apertures in said head, the adjustable brim-supporting frames fitted 25 in said apertures and an adjustable joint uniting the head to the socket.

3. The combination with a suitable support, of the brim-holding frame having straight legs, the head having apertures adapted to 30 receive the legs of the frames, the socket on the head adapted to receive the support, and the ticket-holding rod supported by the head in front of the brim-holding frame.

In testimony whereof I have signed my 35 name in the presence of two subscribing witnesses.

JAMES B. ALLEN.
